(57) **CLAIM**

The ornamental design for a box, as shown and described.

DESCRIPTION

FIG. 1 is a front, top, left perspective view of a box, showing the new design;

FIG. 2 is a rear, top, right perspective view thereof;

FIG. 3 is a front view thereof;

FIG. 4 is a rear view thereof;

FIG. 5 is a right side view thereof;

FIG. 6 is left side view thereof;

FIG. 7 is a top plan view thereof; and,

FIG. 8 is a bottom plan view thereof.

The broken lines of even length illustrate portions of the box and form no part of the claimed design.

The Mounjaro logo forming part of the claimed design is a registered trademark of Eli Lilly and Company.

1 Claim, 8 Drawing Sheets
